UNITED STATES PATENT OFFICE.

HORATIO P. VAN CLEVE, OF CRANFORD, NEW JERSEY, ASSIGNOR TO J. EDWARD OGDEN, OF MOUNTAINVILLE, NEW YORK.

DOOR-OPERATING MECHANISM.

Application filed August 10, 1922. Serial No. 530,959.

To all whom it may concern:

Be it known that I, HORATIO P. VAN CLEVE, a citizen of the United States, and a resident of Cranford, Union County, and 5 State of New Jersey, have invented certain new and useful Improvements in Door-Operating Mechanism, of which the following is a specification.

This invention relates to doors and particularly to doors of the type used for closing large openings in warehouses, pier sheds and structures of like character.

Doors of this type may comprise one or a plurality of sections which in opening 15 are moved vertically and then laterally or inwardly to an inclined or horizontal position.

By swinging the door sections to such an inclined position head room in the warehouse or pier shed is conserved.

This invention relates more specifically to operating mechanism for doors of the type described and the invention has for its 25 object to provide operating mechanism that is compact and self contained whereby space is conserved.

Another object of the invention is to provide door operating mechanism so constructed and arranged that it may be easily 30 and quickly changed from a hand operated device to a motor operated device.

Another object of the invention is to provide mechanism so constructed and arranged that the gear ratio can be easily changed 35 without changing the space requirements for the mechanism.

Another object of the invention is to provide operating mechanism of the class described that can be readily and quickly 40 erected and taken down.

Another object of the invention is to provide an operating mechanism of the class described which will be self lubricated and kept free from dust.

Another object of the invention is to provide operating mechanism of the class described that can be assembled as a complete 45 unit at the shop and delivered and erected without dismantling.

Further objects of the invention will appear from the following description taken in

connection with the drawings which form a part of this application and in which

Fig. 1 is a sectional elevation showing one form of operating mechanism constructed in 55 accordance with the invention.

Fig. 2 is a sectional elevation taken through the wall of the structure in which the door is mounted showing the wall and door sections in section and the operating 60 mechanism in elevation.

Fig. 3 is a front elevation of the construction shown in Fig. 2.

Fig. 4 is an elevation on a smaller scale than Fig. 1 and showing a motor drive for 65 the planetary gearing instead of a sprocket drive.

Fig. 5 is a horizontal sectional elevation of another form of the door operating mechanism.

Fig. 6 is an end elevation or a vertical section of a door having connected thereto the operating mechanism shown in Fig. 5 and

Fig. 7 is a front elevation of the door construction and operating mechanism shown in 75 Fig. 6.

The invention may be briefly described as comprising operating mechanism enclosed in a casing and preferably including one or more sets of planetary gearing connected to 80 drive a rotating member such as a sheave which in turn is connected to the door or door sections to be lifted. In one embodiment of the invention the driving member is carried by a casing detachably connected 85 to the gearing casing above mentioned and this driving member may consist of a motor or of a sprocket wheel adapted to be rotated manually. In another form of the invention, namely, that shown in Figs. 5-7 the 90 planetary gearing is driven by spur gearing which in turn is actuated manually.

Referring first to the embodiment of the invention shown in Figs. 1-4 inclusive, I have shown a portion 10 of a building having 95 a door opening 11 therein and a door comprising a plurality of sections such as a lower section 12 and an upper section 13 adapted to close the opening.

The section 12 of the door carries rollers 100 14 adapted to engage tracks 15 as the door is pulled upwardly and the section 13 has

connected thereto links 16, the opposite ends of which are connected at 17 to brackets 18 affixed or secured to the wall 10. The links 16 operate in a manner to cause the door sections to be swung inwardly after the lower section 12 has been raised to register with the upper section.

The invention about to be described relates particularly to operating mechanism 10 for lifting and swinging doors of the type above outlined. In the form of the invention shown in Figs. 1-4 this operating mechanism is carried by a casing 20 secured by bolts 21 to the wall 10, preferably slightly 15 above and at one side of the door as illustrated in Fig. 3. The casing 20 has mounted therein a plurality of sets A and B of planetary gearing, although one set may be used when the required gear reduction will 20 allow it.

In Fig. 1 I have shown a casing 24 secured to one end of the casing 20 and housing a shaft 25 on which is pinned or otherwise fixedly secured a sprocket wheel 26 25 adapted to be manually rotated. The shaft 25 extends through the rear wall of the casing 24 and into the casing 20 and a spur gear 27 of the planetary set A is mounted on the inner end of the shaft 25. The gear 27 meshes with planet gears 28 of the set A and the gears 28 also mesh with a stationary ring gear 29. The planet gears 28 are mounted on pins secured to a spider 30 and the spider has secured thereto or forming 30 a part thereof, a spur gear 32 arranged to turn freely with the spider on a shaft 31. The spur gear 32 meshes with planet gears 33 which also mesh with the ring gear 29 and are carried by a spider 34. The spider 34 is pinned or otherwise fixedly 35 attached to the shaft 31 mounted in bearings 36. A double chain pocket sheave 37 is keyed as shown at 38 or otherwise fixedly secured to the shaft 31 and is therefore driven thereby.

The sheave 37 may be connected in any suitable manner to the door sections and in the form of the invention shown counterweighting mechanism is provided and is 50 used in connection with the gear drive above described. This counterweighting mechanism comprises a counterweight 40 which is suspended from a double sheave or two single sheaves 41. A pair of chains 42 extends around the double sheave or two single sheaves 41 and around the double pocket sheave 37. Each of these chains is fixedly secured as shown at 43 at one end and has the other end secured at any suitable point such as 44 to the lower door section 12. In the case of the single section door, the lower end of the chain would be similarly secured to a suitable point on the door section.

As shown in Fig. 3 one of the chains 42

extends across the wall above the opening 11 and around an idler 45 and downwardly therefrom to some such point as 44 adjacent the lower end of the side edge of the door section 12. As the two chains 42 may 70 stretch unequally a turn buckle 46 is provided in one of the chains for equalizing the lengths of the chains.

The construction shown in Figs. 1-4 inclusive, may be operated manually by rotating the sprocket wheel 26 or if desired a casing 24' such as shown in Fig. 4 may be substituted for the casing 24 and means such as a motor 50 enclosed within or attached to the casing 24' may be connected 75 to drive the shaft 25' and spur gear 27' carried thereby. Spur gear 27' drives planet gears 28' and thereby rotates the spider 20' connected to shaft 25. In other words either a manual or a motor drive 80 may be used and one of these drives may be substituted for the other without dismantling, taking down or otherwise disarranging the transmission gearing. The construction shown in Figs. 1-4 inclusive 85 operates as follows.

Assuming that the hand drive is utilized the sprocket 26 will be rotated manually by pulling on a chain carried thereby. As 90 a sprocket is rotated the drive will be transmitted through gears 27 and 28 of the first set of planetary gearing A and thence through the spider 30 to the second set of planetary gearing including gears 32 and 33 and the spider 34. The ring gear 29 operates in the usual manner in connection with the gears 28 and 33.

The spider 34 drives the shaft 31 and the sheave 37 is driven by the shaft. The sheave 37 is connected in the manner above 95 described to the door and the rotation of the sheave will cause the door to be raised in the usual manner.

In Figs. 5-7 inclusive, I have illustrated another embodiment of the door operating mechanism. As the door parts in Figs. 5 and 7 are constructed in the same manner as those shown in the preceding figures like parts are indicated by corresponding reference characters in both sets of figures. In this form of the invention the casing 60 is secured to the wall of the building as by bolts 60^A above the opening and houses a set of planetary gearing C. As shown in Fig. 5, a plate or casing member 60' is also secured to the wall, by bolts 61^A intermediate the casing 60 and the wall. The planetary gearing C is driven from a shaft 61 journaled in plate or member 60' having mounted at one end a sprocket wheel 62 by means of which the shaft may be rotated. The shaft 61 also carries a spur gear 63 which meshes with a spur gear 64 and the gear 64 has formed integral therewith or secured thereto a spur gear 65. 100

The gear 65 meshes with planet gears 66 carried by a spider 67 and the spider is keyed as shown at 68 or otherwise fixedly secured to the shaft 69 also journaled in plate 60'. The shaft 69 extends through the gears 65 and 64 and through the rear end of the casing and has secured to its rear end a pocket sheave 70. The sheave 70 is connected by a chain 71 to one side 10 edge of the lower door section 12 adjacent the lower end thereof, as shown at 72.

The opposite end of the shaft 69 is connected by a bolt 69^A to a coupling 75 the opposite end of which is connected by means 15 of a bolt 80 located and placed during the erection and thus permitting sliding and rotary adjustment of the shaft 76 to take up variations in the center to center distance of the lifting chains and in their 20 length. The gap 77 between the ends of the shafts 69 and 76 also permits the removal of the outer casing or casing 60 without disturbing the counterweight mechanism or other parts of the door or operating mechanism therefor. By removing the bolts 60^A and the bolts 69^A and 80, the coupling 75 may be moved along the shaft 76 and the casing 60 and gears therein may be removed for repair or for any other 25 purpose without dismantling the door, links or counterbalancing mechanism.

A pocket sheave 78 is secured to the end of the shaft 76 and is connected to the other edge of the door section 12 by a chain 79

35 The door section in Fig. 7 is shown as swung from the vertical to inclined position by links 16' pivoted at 81 to the upper door section and at 82 on the casing 60', concentric with the shaft 69.

40 The construction shown in Figs. 5-7 inclusive operates as follows. The sprocket 62 is rotated manually thereby rotating the gears 63 and 64 and the central gear 65 of the planetary gearing set C. Although I 45 have shown only one set of planetary gearing, it will be readily understood that a plurality of sets of this gearing may be used as shown in the form of the invention previously described and illustrated by Fig.

50 1. The drive is transmitted from the gear 65 through planet gears 66 and through spider 67 to the shaft 69. The rotation of the shaft 69 will operate the doors by means of the chain connection to the sheave 70 55 and to the sheave 78 carried by the shaft 76 which is connected with the shaft 69 by the coupling 75.

From the foregoing specification it will 60 be clear that the door operating mechanism is simple, compact and will occupy a minimum amount of space. Furthermore it will be evident that the units can be assembled at the shop and can be delivered and erected without dismantling. This will save expense and also insure the proper adjustment

of the various gears and other cooperating parts.

Although certain specific embodiments of the invention have been illustrated and described, it will be understood that the invention is capable of further modification and that further changes in the construction and in the arrangement of the various cooperating parts may be made without departing from the spirit or scope of the invention as expressed in the following claims.

What I claim is:

1. Door operating mechanism comprising a casing, a sheave carried thereby, chains carried by the sheave and connected to the door, planetary gearing in the casing connected to drive said sheave, a shaft for driving said gearing, a second casing detachably connected to the first casing and means carried by the second casing for driving 85 said shaft.

2. In combination, a door, a casing, a shaft mounted on and extending through said casing, links pivoted on an axis coinciding with the axis of said shaft and to 90 said door, and door operating mechanism including gearing in said casing, sheaves driven by said gearing and cables extending around and driven by said sheaves and connected to said door.

95 3. Door operating mechanism comprising a casing, a sheave mounted therein, cables carried by the sheaves and connected to the door, planetary gearing in the casing connected to drive said sheave, a shaft for 100 driving said planetary gearing, a second casing, detachably connected to the first casing and means carried by the second casing for driving said shaft.

105 4. In combination, a door, and operating means therefor, including a driven shaft, a sheave affixed to said shaft, planetary gearing for driving said shaft, means connecting the sheave to the door and counterbalancing mechanism connected to said connecting means, and a casing surrounding said shaft sheave and gearing.

110 5. In combination, a door, lifting chains connected to the side edges thereof and means for operating said chains including 115 a pair of spaced shafts in axial alinement, each of said shafts being connected to one of said chains, a telescoping connection between said shafts, said connection comprising an elongated coupling covering the space between the shafts and overlapping the proximate ends of the shafts, a casing surrounding one shaft, and means including planetary gearing mounted in said casing for driving said shaft.

120 6. In combination, a door, a casing, a shaft mounted in and extending through said casing, links pivoted on an axis coinciding with the axis of said shaft and to 125 said door, and door operating mechanism

including planetary gearing in said casing, sheaves driven by said gearing and cables extending around and driven by said sheaves and connected to said door.

5. 7. In combination, a door, a casing, door operating mechanism including gearing in said casing, a shaft extending through said casing and a sheave mounted thereon and connected to said door and a link pivoted 10 on said casing on a pivot concentric with said shaft and pivoted to said door.

8. In combination, a door, door operating mechanism including a pair of shafts disposed above the side edges of the door, 15 gearing for driving one shaft, and a coupling slidably and rotatably connected to one shaft and connected to the other shaft, the connected ends of the shafts being spaced from each other.

20 9. In combination, a door, lifting chains connected to the side edges thereof and means for operating said chains including a shaft, gearing for driving said shaft, a

second shaft, a telescoping connection between said shafts, and a casing surrounding said gearing, said connection being movable on one shaft to permit the removal of the casing and gearing without dismantling the door. 25

10. In combination, a door, lifting chains 30 connected to the side edges thereof, and means for operating said chains including a shaft disposed above one side edge of the door, gearing for driving said shaft, a second shaft extending to the other side edge 35 of the door, sheaves secured to said shafts for operating said chains, a casing enclosing said gearing, a coupling connecting said shafts and slidably on one of them, said shafts having their contiguous ends spaced 40 apart to permit the removal of said gearing and casing therebetween without dismantling said door.

In witness whereof, I have hereunto set my hand this 13th day of June, 1922.

HORATIO P. VAN CLEVE
